UNITED STATES PATENT OFFICE.

MICHAEL HOFFMANN, OF IVANHOE, MINNESOTA, ASSIGNOR OF ONE-HALF TO WALTER J. DALTON AND ONE-SIXTH TO FRANK R. KLUCZNY, BOTH OF IVANHOE, MINNESOTA.

ELECTRIC SWITCH.

1,221,325.

Specification of Letters Patent. Patented Apr. 3, 1917.

Application filed January 18, 1916. Serial No. 72,783.

To all whom it may concern:

Be it known that I, MICHAEL HOFFMANN, a citizen of the United States, residing at Ivanhoe, in the county of Lincoln and State 5 of Minnesota, have invented certain new and useful Improvements in Electric Switches, of which the following is a specification.

My invention relates to a new and useful improvement in an electric switch and more 10 particularly to a combination lock switch.

The primary object of the invention is the provision of an electric switch for closing a circuit which can only be operated by a person conversant with the combination 15 to which the terminals of the electric wires are connected.

A further object of the invention is the provision of a switch of this character which is simple and inexpensive in construction 20 and which may be used with the ignition apparatus of automobiles or motor driven vehicles and will prevent the unlawful use of motor vehicles which may be temporarily left in public thoroughfares, or other places.

With these and other objects in view the invention consists in the novel details of construction and arrangement of parts which will be more clearly understood from 25 the following description and drawings, in which,

Figure 1 is a fragmental top plan view of the interior of an automobile, showing my improved switch applied to the dashboard thereof,

Fig. 2 is a top plan view of the switch,

Fig. 3 is a plan view of the contact plate showing the switch arms, and

Fig. 4 is a transverse vertical section through the switch.

In the drawings the letter A indicates the dashboard of a motor driven vehicle and my switch is designated generally by the letter B.

My switch comprises a base plate 1 which 45 may be of any desired insulating material and has a plurality of metal disks embedded in the top face thereof and held in position by means of the bolts 3 which pass through the base 1 and engage the disks 2.

These contact disks 2 are preferably arranged in a circle and there is an inner and outer row thereof, as is more particularly shown in Fig. 3 of the drawings. The wires 50 of the ignition system are indicated at 4 and 5 and are adapted to be connected to

any of the bolts 3 which are connected to the contact disks 2. The wire 4 is adapted to be connected to one of the bolts forming a part of the inner circle and the wire 5 may be attached to one of the bolts forming 60 a part of the outer circle of contacts. As is clearly shown in Fig. 4 of the drawings, the contact disks 2 extend above the top of the insulating plate 1.

A plurality of posts 6 are connected to 65 the base 1 and support the top plate 7 of my switch. This top plate 7 is provided with a plurality of openings, indicated at 8, adapted to receive bolts or other suitable fastening means for securing the switch to 70 the dashboard. The plate 7 is provided with a central depressed portion having an opening therein thereby forming an inwardly extending flange indicated at 9 and the purpose of which will be presently described. A plate 10 is adapted to be received upon the plate 9 and is also provided with a central depression having an opening 75 therein, thereby forming an inwardly extending flange 11 upon which is received a 80 plate 12 having a central opening therein. A bolt 13 is adapted to pass through the central opening of the plate 2 and also through a central opening in the base 1. This bolt is provided on the upper end with 85 a knob or handle 14 and a cotter pin 15 is adapted to pass through an opening in the lower end thereby holding the bolt in position. A knob or handle 16 is secured to the plate 10 in any desired manner and the purpose of which will be presently described.

A sleeve 17 is connected to the bolt 13 in any suitable manner and has a spring contact arm 18 formed on the lower end thereof and adapted to contact with the contact 95 disks 2 of the inner circle of disks. A sleeve 19 is rotatably mounted upon the sleeve 17 and has an arm extending at right angles thereto as indicated at 20 and from which depends a contact arm 21 adapted to engage with the contact disks 2 of the outer circle of disks. The arm 20 is adapted to be secured to the underside of the disks 10 as clearly shown in Fig. 4 of the drawings.

The top plate 7 is provided with two rows 105 of letters or figures, letters being shown in Fig. 2 of the drawings, and each of the plates 10 and 12 are provided with a mark which may be used in forming a part of the combination.

Having fully described the details of construction it is thought that the advantages and operation of my switch will be clearly understood. The switch is adapted to be connected to the dashboard of the vehicle by means of bolts or other suitable fastening means passing through the openings 8 in the top plate 7. By this arrangement the lower base plate 1 may be inserted through an opening in the dashboard whereby the top plate will lie substantially flush therewith. When the contact arms 18 and 21 are in the position illustrated in Figs. 3 and 4 of the drawings, the circuit is closed and the ignition apparatus can operate. Should the owner of the vehicle desire to temporarily leave the same, the circuit may be broken by taking hold of the knobs or handles 14 and 16 and rotating the plates 10 and 12, respectively. By this operation the contact arms are removed from those contact disks 2 connected with the wire terminals and the circuit is thereby broken. When it is again desired to operate the vehicle it can only be done by closing the circuit and this can be done only by the person knowing the combination of the switch. The disks can be rotated until the right combination is secured and then the circuit will be again closed and the ignition apparatus can operate. By providing the depressions in the top plate 7 and in the plate 10, all parts of the top will be flush and thereby give a neat appearance. The combination can easily be changed by merely connecting the wires 4 and 5 to different bolts 3.

Having thus fully described my invention what I claim as new and desire to secure by Letters Patent is:

A switch comprising a supporting plate 40 having a centrally opened recess, a dielectric plate held beneath the supporting plate, concentric rows of contacts arranged on the dielectric plate, one contact in each set forming the terminal of an electric circuit, a rotatable plate mounted in the recess of the supporting plate and having a centrally opened flanged recess, a turning knob on the rotatable plate, a rotatable staff having a knob, the staff being disposed coaxially with the supporting and dielectric plates, a bracket secured to the rotatable plate having a sleeve at one end circumscribed on and spaced from the staff, the bracket having at the other end a contact arm adapted to engage one of the rows of the contacts, a second sleeve disposed between the first named sleeve and the staff, the second sleeve being removably secured to the staff and including a contact arm for engaging the other of the rows of the contacts, a washer for the staff arranged to rest in the recess of the rotatable plate and support the knob of the staff, and a cotter pin for the staff to retain the staff, washer, and rotatable plate in position. 55

In testimony whereof I affix my signature in presence of two witnesses.

MICHAEL HOFFMANN.
